EARTH MOVING SCRAPER

Edward Meyer, Sioux Falls, and Ted J. Poppe,
Parker, S. Dak.; said Poppe assignor to said
Meyer

Application April 4, 1945, Serial No. 586,490

6 Claims. (Cl. 37—126)

1

This invention relates to improvements in cable operated earth moving scrapers, and in particular to a method and apparatus for retrieving and replacing sliding sheave blocks and control cables which have become displaced as by the breakage of control cables.

The structure of certain machines of this type includes an open topped inclined channel or guideway in which sliding and fixed sheave blocks are located. Control cables, generally of steel, pass over the sheaves in these blocks for the purpose of operating the movable parts of the machine.

Large forces are transmitted and applied by these cables and they occasionally break. When such breakage occurs the sliding sheave blocks generally slide down in the channel or guideway and become wedged therein, together with the flexible steel cable which normally passes over the pulleys in the sheave blocks. The sheave blocks and pulleys, being heavy, greasy, and dirty, are difficult to move and return to their operative position. This operation normally takes an hour or more when done by customary methods and with the usual tools.

We have devised a simplified method and apparatus for returning the sliding sheave blocks and the steel cables thereon back to their normal position in a very small time and substantially without any expenditure of manual labor in the operation.

It is accordingly a primary object of our invention to provide an improved method and apparatus for retrieving and replacing displaced units of a mechanism including sliding sheave blocks and the sheaves and cables thereon.

It is another object of our invention to utilize certain relative motions between normally operating elements of a flexible, cable operated device to retrieve and return other elements to their normal operating position when displaced therefrom.

It is another major object of our invention to provide an attachment for earth moving cable operated machines which is operable to return elements of the cable system to normal position when displaced therefrom.

Figure 1 is a side elevation, with parts broken away illustrating an embodiment of our invention applied to a machine of the general type with which it is adapted to be used.

Figure 2 is an enlarged view of a part of Figure 1 showing our device arranged for retrieving a sheave block.

2

Figure 3 is a partial sectional view along line 3—3 of Figure 2, looking in the direction of the arrows.

The machine shown in Figure 1 is one embodying a control cable arrangement similar to that shown in the Le Tourneau Patent No. 2,288,629 and a lift control mechanism similar to that shown in the Le Tourneau Patent No. 2,288,630, both of these patents having issued on July 7, 1942.

As shown in Figure 1, the scraper comprises side frames 11, an inclined beam 12 and a wishbone frame 13 joining the front part of the side frames to the upper and front part of the beam 12. The scraper is supported at its rear end by wheels 14. The front part of the scraper is attached by a pivoted connection 15 to front wheels 16 on a gooseneck unit 17. A tripod frame having a pair of legs 18 and a front leg 19 joined at their upper ends is fastened at its lower ends to the unit 17 as shown. A bracket 20 is fastened to the top of the beam 12 and the frame 13 at their juncture, the bracket having spaced walls 21 and 22 as shown in Figure 3, there being a push bar 23 having a sliding movement within the bracket 20 and longitudinally of the scraper. At its front end the push bar 23 has a pivoted connection to the tripod formed by the legs 18 and 19. The sliding movement of the push bar within the bracket 20 may be facilitated by a pair of rollers 24 and 25 journaled for rotation on the walls 21 and 22 and engaging horizontally extending flanges formed in any suitable manner, for example, by recesses in the side walls of the push bar 23 as illustrated in Figure 3.

A sheave 28 is also journaled for rotation between the walls 21 and 22 of the bracket 20 as shown, having a horizontal shaft 29 passing through the walls. At its rear end the push bar 23 has a sheave 30 journaled about a horizontal shaft 31. A flexible steel control cable 32 is fastened at one end to a fitting 33 on the top of the bracket 20. The cable 32 passes backward, around the sheave 28, then forward over the sheave 30, and through a sheave 34 fastened to the gooseneck 17 to a power operated device such as a winlass on the tractor or other device (not shown) which pulls the scraper by means of a draw bar 35 or the like. As will be understood by those skilled in the art, when the cable 32 is pulled it moves the push bar 23 forward through the bracket 22, thus separating the bracket 20 and the top of the tripod so that the scraper is lifted out of contact with the ground, as in the position in which it is shown in Figure 1. A re-

lease of the tension in the cable 32 results in the lowering of the scraper until it rests upon the ground, and the push bar, bracket, and tripod are moved to substantially the relative positions shown in Figure 2. It is to be understood that more than one sheave 30 may be used and that a sheave may be mounted on the bracket to obtain a power increasing arrangement to lift the weight of the scraper, but the arrangement shown is sufficient to the illustration of the application of our invention, as will be apparent. It is also to be understood that our invention is equally applicable to the arrangement shown in the aforesaid Patent 2,288,629 wherein the push bar is pivotally attached to the juncture of the wishbone frame and the inclined beam, and has sliding engagement with the tripod extending upward from the gooseneck, since as will be described, the operation of our invention results from the separation of said juncture and tripod when the scraper is lifted from the ground.

On the top of the beam 12 and substantially parallel thereto, the scraper has an open topped channel including a pair of vertical side walls of which only one is shown, identified by the reference number 38, the other being removed to show the disposition of the sheaves and cables therebetween. At the rear of the aforesaid channel are located a pair of fixed mountings 39 and 40 having sheaves 41, 42 and 43 rotatably mounted thereon. Between the spaced walls 38, which form guideways for them, are a pair of sliding sheave blocks 44 and 45, each having rotatable sheaves therein. A main pull cable 46 having its front end attached to a power driven windlass or the like on the tractor or other device, passes through and around the sheave blocks 44 and 45 and the sheaves 41, 42 and 43, serving to pull the sheave blocks down the incline of the guideway formed by the walls 38, whereby cables 47 and 48 attached to the sliding blocks, operate to pull the tailgate 49 forward and the apron 50 upwards. The operation of the cable and sheave arrangement described is similar to that described and shown in Figure 2 of the aforesaid Patent 2,288,629 and is well known to those skilled in the art.

It occasionally happens that one or more of the aforesaid cables breaks. When this occurs there is generally a tension in the cables passing over the sheaves 41 to 43 to and from the sheaves in the sliding blocks 44 and 45, and the sliding blocks will slide downwardly and to the left as viewed in Figures 1 and 2. This results in a jamming of the sliding blocks 44 and 45, together with the loosened cable, within the guideway between the walls 38. Heretofore, in order to retrieve the sliding sheave blocks and cable, which are heavy, greasy, and dirty, at least an hour of hard manual labor has been required. By the use of our invention, the manual labor is substantially eliminated and the time necessary has been reduced to a negligible amount.

As best shown in the enlarged view of Figure 2, where the cables between the walls 38 are not illustrated in order to simplify the showing, sliding sheave blocks 44 and 45 have hooks 51 and 52 fastened to them as shown in the drawings. One of the legs 18 of the tripod on the gooseneck 17 has a series of similar hooks 53, 54, etc. Another similar hook 55 is attached to the sheave block 30, on the bottom portion as shown. A pulley 56 rotatable about a substantially horizontal axis is mounted on a gusset plate 57 or the like attached to the tripod near the top thereof.

A flexible steel cable 58 normally has one end hooked over the hook 55, then passes over the pulley 56 and downward to the lowermost hook 53 on the leg 18. Suitable means are provided on the ends of the cable to permit it to be hooked in this manner. When the scraper is operating normally the cable 58 is in the above described location, being stored in such position so that it is available for immediate use without threading it through the pulley 56. It will be found convenient to have a spring attached to the cable between one end and the hook at that end, so that there will be no slack in the cable when stored.

Now when one of the control cables breaks and the sheave blocks slide down as described before, the cable 58 is brought into operation. The upper end of the cable is unhooked from 55 and placed over the hook 52 on the sheave block 45. In order to do this the other end of the cable must be unhooked from the lowermost hook on the leg 18. Cable 32 is slackened so that the scraper rests upon the ground and the push bar 23 moves back to the relative position shown in Figure 2. After placing one end of the cable over the hook 52 the cable is pulled tight and the other end placed over the hook on leg 18 nearest to that end. No spring is used to take the slack out of the cable, as when it is merely stored. With both ends of the cable hooked as described the cable 32 is wound on the windlass again so that the scraper is lifted from the ground and the push bar 23 moved forward to separate the bracket 20 and the top of the tripod. As this operation proceeds the cable 58 will pull the sheave block 45 with its attached cables upwardly and to the right as viewed in Figures 1 and 2. If the sheave block 45 has not been returned to its proper position by one such operation it is held in place while the scraper is lowered to the ground again. Now the end of cable 58 is moved to a lower hook on the leg 18. After this the scraper is raised from the ground again as described before, moving the block 45 farther upward and to the right. In order to keep from moving the block 45 too far, its movement must be observed and the raising of the scraper stopped at the proper point. After the sheave block 45 is retrieved in this manner it is fastened in its proper place and the sheave block 44 is retrieved in the same manner. After they have both been retrieved the cable 58 is unhooked and returned to its storage position, out of the way, and any necessary repair to the cables passing through the sheave blocks may be proceeded with.

By the use of our method and apparatus the retrieving of the sheave blocks is made a simple and quick powered operation rather than the awkward time-consuming manual operation as heretofore practised. The cost of the cable and hooks, etc., and their installation costs are small, and the savings effected are large.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. In an earth-moving implement; a scraper having a wheeled support at one end and adapted to rest upon the ground at the other end; loading and unloading means on said scraper; means for operating said loading and unloading means comprising a combination of guideways, sliding sheave blocks and a cable running through said blocks; lifting means for said other end of said scraper, pivotally attached to said scraper and having a portion operable to swing away from said scraper and said combination when lifting said other end; and means constructed and arranged to connect the sliding blocks of said combination temporarily to said portion, for relative movement in the same direction with respect to said scraper as said portion when said portion swings away from said scraper, to shift said sliding blocks when jammed in said guideways.

2. In an earth-moving implement, a scraper having a wheeled support at one end and adapted to rest upon the ground at the other end; a first tripod structure fixed to the top of said scraper and including an inclined beam; an inclined guideway supported by said beam; loading and unloading devices on said scraper; means for actuating said loading and unloading devices comprising a combination of sliding sheave blocks and cables within said guideway; a second tripod structure pivotally attached at a base thereof to said scraper at the said other end; means having a pivoted connection with the top of one of said tripod structures and a sliding connection with the top of the other of said tripod structures; means operable to drive said last mentioned means to separate the tops of said tripod structures whereby the said other end of said scraper is lifted from the ground; and a cable adapted to be temporarily connected at one end to either of said sliding sheave blocks and at the other end to the apex of said second tripod, whereby movement of the apex of said second tripod with respect to said first tripod structure will shift the sliding sheave block to which it is connected towards the apex of said first tripod structure.

3. In an earth moving apparatus wherein a scraper unit is operated by control cables passing through and around a system including sliding sheave blocks having sliding motion in a guideway affixed to the top of said scraper unit and wherein one end of said scraper unit is raised from the ground by rotating a tripod frame which is pivotally attached at a base portion thereof to said one end of said unit, there being a push bar having pivoted engagement at one end with the top of the tripod and sliding engagement along its length in a bracket on the top of said guideway and power operated means to actuate the push bar and rotate the tripod about its pivot; a series of hooks along

one leg of said tripod, a hook on said push bar adjacent its free end, a hook on each said sheave block, a pulley adjacent the top of said tripod, and a cable passing through said pulley and having means on each end for engaging any of said hooks, whereby one end of said cable is attachable to said hooks on said leg, and the other end of said cable may be attached alternately either to the hook on said push bar or to a hook on one of said sheave blocks.

5. The method of retrieving the sliding sheave blocks and cables which slide in a guideway of a cable operated load moving apparatus wherein one part of said apparatus is movable with respect to the guideway, comprising connecting said movable part of said apparatus to one of said sheave blocks by a connection extending substantially in line with the normal direction of movement of said sheave blocks, and applying power to said movable part to shift it and thereby pull the sheave block to its normal position in the guideway.

25. A pulley block retriever for use with a cable operated, load moving framework pivotally connected to a gooseneck unit and providing a guideway for a pulley block comprising a bracket supported by said framework; a push bar supported at one end from said gooseneck unit and slidably connected to said bracket; a sheave journalled at the free end of said push bar; power operated cable means connected at one end to said bracket and passing around said sheave so as to move said push bar relative to said bracket; cable securing and guiding means carried by said gooseneck unit; and a second cable operably associated with said cable securing and guiding means and having one end adapted for attachment to a jammed, out-of-position pulley block disposed in said guideway to restore said pulley block to its normal working position upon said relative movement of said push bar and bracket.

30. 40. 45. 50. 6. The combination defined in claim 4 wherein said cable securing and guiding means comprises a hook on said gooseneck unit for receiving said other end of said second cable and a second sheave journalled on said gooseneck unit and arranged to direct the run of said second cable between said one end of said cable and said second sheave in a direction substantially parallel to said guideway.
